UNITED STATES PATENT OFFICE.

WILLIAM J. KNOX, OF OWEGO, NEW YORK.

MARKING DEVICE FOR SHOE PARTS AND THE LIKE.

Application filed May 21, 1927. Serial No. 193,370.

My invention pertains to a device for marking parts of shoes for the purpose of assisting and expediting the process of matching or lapping the parts for sewing, and for other purposes.

It has been the usual practice in the past to so mark the shoe parts by hand with the use of a form and punch. Such a process is slow and tedious and it is the purpose of my invention to provide a device by means of which a complete set of parts for a given shoe may be simultaneously and quickly marked.

A further object of my invention is to provide such a device with pattern members which may be made up for any desired marking and quickly inserted or removed from the marking device.

A still further object is to provide a device which has a relatively fixed or stationary guide pattern for receiving the parts to be marked and a movable punching pattern cooperating with said guide pattern, whereby all the parts may be punch marked simultaneously.

An important feature of my invention lies in the means for readily removing both the guide pattern and the punching pattern, whereby they may be replaced in the device with others of like character arranged with a different punching design.

Other objects and advantages in details of construction and operation will be apparent as the description proceeds, reference now being had to the figures of the drawings wherein like reference numerals indicate like parts.

In the drawing:—

Figure 1 is a perspective view of my improved punching device in open position.

Figure 2 is a similar view showing the device closed.

Figure 3 is a side view of the device, certain parts being broken away for clearness of illustration.

Figure 4 is a detail perspective of one corner of the lower half of the device.

Figure 5 is a detail perspective view of a modified form of marking pattern.

Figure 6 is a detail plan view of a shoe part punched in my improved device.

Figure 7 is a detail cross sectional view illustrating the method of securing the punch members in the patterns.

Figure 8 is a similar view illustrating

the method of securing the guide pin in the patterns.

In preparing pieces of leather or other material for assembly into shoe form, it is the practice to first cut such piece to size and shape according to the shoe to be made and then to mark with a punch around certain edges of the cut pieces, the point to which the same will overlap with and be secured to its component part. Obviously, if several of such shoe parts can be so punch marked at one time accurately, a great saving of time and labor is accomplished. To this end, I have provided an improved punch marking device, possessing many advantages and which will now be described.

There is provided a base member 1 preferably of heavy steel and which is provided on its top surface with a recess 2 within which is adapted to be placed a guide pattern 3. This guide pattern is preferably formed of heavy cardboard or other suitable material and when placed within the recess 2 has its upper surface lying slightly below the upper surface of the base member 1. Means are provided for retaining the guide pattern 3 in such position comprising screws 4 placed about the edges of the recess 1, and between the heads of these screws 4 and the guide pattern 3, are washers 5 having one edge cut away as at 6 whereby said washers may be turned upon loosening of the screws 4 to bring such cut away edge into alignment with the edge of the guide pattern 3 permitting the same to be removed or inserted within the recess 2. The edges of the base member 1 are recessed adjacent the screws 4 as at 7 to permit such turning of the washers 5. As shown in Figure 1, the washers 5 have been turned so that their uncut edges overlie the guide pattern 3 and with the screws 4 tightened in such position, such guide is securely held within the recess 2. Guide pins 8 are provided in the base member 1, such pins passing through suitable eyeleted openings in the guide pattern 3, whereby such pattern is always accurately positioned within the base member 1.

This guide pattern 3 is provided with a plurality of guide pins or studs 9 projecting slightly above the surface of the pattern and arranged in the proper position and design to receive the shoe parts 10 which are placed on the guide pattern 3, such as is shown in dotted lines in Figure 1. Obviously for a

given size and shape of a part to be marked, the guide pins 9 are arranged to accommodate such shape or design of part. It will be understood that any number of guide 5 patterns may be made up for as many different designs, shapes or sizes of shoe parts to be marked as desired or necessary, and all of such guide patterns are made the same size and adapted to be received within 10 the base member 1 for the marking operation.

Figure 8 illustrates one method of securing these guide pins to the pattern 3 and includes a headed stud which may be staked or otherwise crimped or riveted into the 15 under surface of the guide pattern as at 11.

The base member 1 is provided at its rear edge with two upstanding bearings 12 through which passes a shaft 13 forming a pivot for the swinging top plate 14. This top plate is provided along one edge with integral bearings 15 surrounding the shaft 13 and keyed thereto as at 16. A coil spring 17 is anchored at its ends in the base plate 1 as at 18, is coiled about the shaft 13 and has a portion thereof secured as by staples or other suitable means 19 to the upper side of the top piece 14, the tension of the spring 17 normally exerting its tension to raise such 30 top piece upwardly and out of engagement with the base plate 1. A stop lug 20 is secured to one end of the shaft 13 in position to engage with the rear edge of the base plate 1 and thus limit the upward 35 movement of the top piece 14. This top piece 14 is provided on its outer surface with reinforcing ribs 21, one of which curves away from the front edge of the top piece 14 as at 22 to provide a finger space 40 for the operator along the edge of the top piece whereby the same may be rocked downwardly on its pivot.

The under surface of the top piece 14 is provided with a recess 23 to receive a punch 45 pattern 24 of substantially the same size and shape as the guide pattern 3. This punch pattern 24 is removably secured within the recess 23 in the same manner as the guide pattern 3 is secured within the base member 1, that is by means of screws 25 and eccentric washers 26. Guide pins 27 are 50 also provided on the under surface of the top piece 14 for accurately positioning the punch pattern 24.

Secured to the punch pattern 24 are the 55 punch members 28, pointed at their projecting ends and as shown in Figure 7 comprising the pin 28 driven or otherwise rigidly secured within a plug 29 which plug is staked or otherwise secured as at 30 to the punch pattern 24.

These punches or markers 28 are so arranged on the pattern 24 as to engage with and stab the shoe parts 10 arranged on the 60 guide pattern 3, at precisely the desired

points. The arrangement of the punches 28 is of course predetermined for a given shoe part to be marked and will of course be a punch pattern 24 corresponding to the guide pattern 3 for a given set of parts to be 70 marked.

The operation of my improved punch marker is as follows:—Assuming that it is desired to punch mark a certain quantity of shoe parts of a given size and design, the 75 guide and punch patterns 3 and 24, previously prepared for that particular size and design of shoe parts, are placed within the recesses 2 and 23 respectively of the base member 1 and top piece 14 and secured 80 therein by means of the eccentric washers 5 and 26. The operator now lays a complete set of the parts to be marked on the guide pattern 3 in cooperation with the guide pins 9. The top piece 14 is now swung downwardly on its pivot to the position shown in Figure 2 at which operation the punch members 28, punch the openings 31 (see Figure 6) in the parts 10 in exactly the desired 85 position with respect to the edges of said parts. In this manner, a complete set of shoe parts may be punched simultaneously and accurately thus eliminating the necessity of punching each piece separately and by a single hand punch.

After the particular size and design of shoe parts have been thus marked and it is desired to similarly mark another set of a different size or shape, the guide and punch 90 patterns 3 and 24 are removed from the device and other patterns inserted in their place corresponding to the parts now to be marked and the operation repeated.

It is frequently desirable on certain grades of shoes to provide parts thereof with fancy 105 stitching or other decorative work. In such case, it is desirable to mark on the shoe parts to be so decorated a guide line which the 110 decorator can follow. The punch marks above described and used for lapping purposes are not suitable for this type of marking and for this purposes, there may be provided a modified form of pattern to go in the top piece 14 of the marking device. Such a modified form of pattern is illustrated 115 in Figure 5 wherein the pattern is indicated at 32 and mounted thereon as by rivets or other suitable means 33 is a marking tool provided with an upstanding marking edge 34 of a design corresponding to the 120 guide pattern in the lower or base member 1 which guide pattern has of course been laid out to receive a given size and shape of shoe part to be marked. In the use of this 125 form of marker, the marking edge 34 is preferably painted or coated with a color substance which will leave a colored line or mark on the shoe part corresponding to the marking edge 34.

In using this type of marker, the mark- 130

ing edge 34 may include extensions or independent portions of the same character for the purpose of placing the lap marks on the material at the same time the guide 5 marks for decorative purposes are placed thereon. In such event, it is unnecessary to use the punch type of marker for the lap markings for in this manner both the decorative markings and lap markings can 10 be simultaneously made on the shoe parts. This form of marker, however, is to be used preferably only when decorative marking is to be made, for the punch form of markings is much easier inasmuch as the marker does 15 not have to be painted or coated with a color substance before each marking operation.

Of course, many changes may be made in details of construction and arrangement of parts without departing from the spirit 20 of my invention. I do not limit myself, therefore, to the exact form shown and described other than by the appended claims.

I claim:—

1. A marking device for shoe parts and 25 the like, comprising a base member, a member movable relatively thereto and engageable therewith, a guide pattern on said base for receiving the parts to be marked, and a marking pattern on said movable member 30 carrying means for marking said parts while on said guide pattern, said patterns being readily removable as units from said members.

2. A marking device for shoe parts and 35 the like, comprising a base member, a member movable relatively thereto and engageable therewith, a guide pattern on said base for receiving the parts to be marked, said pattern comprising a card provided with 40 guide pins and removably secured to said base member, and a marking pattern removably secured to said movable member and provided with marking means.

3. A marking device for shoe parts and 45 the like, comprising a base member provided with a removable pattern having guide pins thereon for receiving said parts, a swinging member hinged to said base member and likewise having a removable pattern, said last named pattern being provided with 50 means for marking said parts while on said guide pattern and when closed upon said base plate.

4. A marking device comprising two members, one adapted to close upon the other, 55 and removable patterns in said members, one of said patterns guiding the parts to be marked and the other carrying marking devices.

5. A marking device for shoe parts and 60 the like, comprising co-acting members adapted to be closed one against the other, carrying removable patterns between which said parts are received and marked when said members are closed against each other.

WILLIAM J. KNOX.
